US00D986577S

(12) **United States Design Patent** (10) **Patent No.:** **US D986,577 S**
Cristobal (45) **Date of Patent:** **** May 23, 2023**

(54) **SHOE**

(71) Applicant: **NIKE, Inc.**, Beaverton, OR (US)

(72) Inventor: **Stefan B. Cristobal**, Beaverton, OR (US)

(73) Assignee: **NIKE, Inc.**, Beaverton, OR (US)

(**) Term: **15 Years**

(21) Appl. No.: **29/864,041**

(22) Filed: **May 6, 2022**

(51) LOC (14) Cl. **02-04**

(52) U.S. Cl.

USPC **D2/972**

(58) **Field of Classification Search**

USPC D2/943, 946, 947, 969, 972, 973, 974, D2/977, 978

CPC .. A43B 5/06; A43B 5/10; A43B 13/04; A43B 13/026; A43B 13/023; A43B 11/00; A43B 15/00; A43C 11/00; A43C 5/00

CLAIM

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; and, FIG. 5 is an opposite side view thereof.

The broken line showing of the racetrack shaped region forms no part of the claimed design. The broken lines depicting the remainder of the shoe form no part of the claimed design.

1 Claim, 5 Drawing Sheets
